G. C. JENSEN.
LOCKING CONSTRUCTION FOR LEVERS.
APPLICATION FILED FEB. 13, 1918.

1,275,039.

Patented Aug. 6, 1918.

WITNESS:

Wm G. Drew

INVENTOR.

George C. Jensen

BY

Ackers & Tolten

ATTORNEYS.

UNITED STATES PATENT OFFICE.

GEORGE C. JENSEN, OF OAKLAND, CALIFORNIA.

LOCKING CONSTRUCTION FOR LEVERS.

1,275,039.

Specification of Letters Patent. Patented Aug. 6, 1918.

Application filed February 13, 1918. Serial No. 216,968.

To all whom it may concern:

Be it known that I, GEORGE C. JENSEN, a citizen of the United States, residing at Oakland, in the county of Alameda and State of California, have invented certain new and useful Improvements in Locking Constructions for Levers, of which the following is a specification.

The present invention relates to an improved lock for gear shift levers of motor vehicles wherein a simple construction is provided in the form of a longitudinally movable locking bolt, and which is adapted for engaging a portion of the lever to lock the same from operative movement.

The invention is illustrated in the form of a unit construction for attachment to a lever case or gear case housing, and when in locked position being prevented from removal therefrom, while in its released position it is capable of ready detachment. However, the construction may be formed directly in the lever casing or in the gear case housing. When constructed as a unit my improved locking device is capable of attachment to levers of any well known construction by providing an opening in the casing thereof in such position that the locking bolt carried by the unit is capable of engagement with the lever to lock the same from operation when projected through such opening.

By my construction I provide a locking unit capable of being manufactured at little cost and designed for ready attachment to a lever casing or gear case housing, and when attached forming a part thereof, the construction being capable of being in locked and unlocked position relative to the lever while remaining attached to its support.

To more fully comprehend the invention, reference is directed to the accompanying drawings, wherein—

Fig. 1 is a view in vertical section of the preferred embodiment of my invention.

Fig. 2 is a transverse sectional view taken on line 2—2 of Fig. 1.

In the drawings, wherein like characters of reference designate corresponding parts, 1 indicates a suitable lever casing provided in its upper wall 2 with the lever guide slots 3 connected by the transverse selective slot 4. In the illustration a gear case housing 5 is shown as connected to the lever casing 1 and said housing is provided with a port or opening 6 having a threaded wall.

Extending transversely through the lever casing 1 and the gear casing 5 is a suitable shaft 7 preferably mounted to axially rotate and in this construction the same is designed for co-operation with the vehicle brakes, not shown.

Extending through the dividing wall 8 between the housing 1 and gear case housing 5 is a tubular sleeve 9 fulcrumed on the shaft 7, and said sleeve carries at one end the operating lever 10 extending upwardly through the casing 1 and guided in its operative and selective movement by the slots 3 and 4. The other end of said sleeve 9 connects with the gear element shifting hub 11 from which depends the gear element shifting arm 12, said arm being preferably disposed downwardly in the gear case 5 and co-operating in any suitable manner with the gear elements therein.

The hub 11 is designed to lie below the opening 6 and is provided with a recess 13 adapted when the lever 10 is in alinement with the selective slot 4 to lie below the opening 6 for engagement by the lower end of a longitudinal movable locking bolt 14 carried by a bore 15 in a locking bolt casing 16 adapted for screw threaded attachment at its lower end in the opening 6. The bolt 14 is of a length to project beyond the ends of the bore 15 and is normally forced outwardly by a coil spring 17 seated in the groove 18 in the side thereof, said spring being held under compression at its lower end by a guide pin 18' threaded into the casing 16 and projecting into the groove 18, said pin preventing axial rotation of the bolt 14 is said bore and limiting the upward movement of the locking bolt by contacting with the lower end of said groove 18. The bolt when in its retracted or dotted line position (Fig. 1) is designed to lie with its lower end raised above the upper edge of the opening 6 thereby permitting the removal of the casing 16 from the opening 6, but when depressed and lying in a full line position (Fig. 1) the lower end of the bolt extends through an offset portion 19 in the opening 6 and is received at its extreme lower end in the recess 13, thereby locking the casing 16 from removal from the opening 6 and at the same time locking the lever from movement. A transverse recess 20 is formed in the locking bolt 14 and within the same is adapted for reception the tongue 21 of a longitudinal movable bolt locking

pin 22 positioned within a bore 23 formed preferably at right angles to and communicating at its outer end with the bore 15.

A spring 24 is mounted in the bore 23 in rear of the bolt locking pin 22 and forces the same outwardly for engagement with the locking bolt 14.

A suitable recess 25 is formed in the side wall of the bolt locking pin 22 and into the same projects a finger 26 disposed eccentrically of a rotatable locking barrel 27 positioned within a casing 28, said barrel being controlled by the rotation of a suitable key 29 adapted for insertion within the barrel 28. A suitable gasket 30 is interposed between the meeting surfaces of the locking bolt casing 16 and the wall of the gear case surrounding the opening 6 to insure a tight connection between the two with the bolt 14 in alignment with the offset portion 19 of the opening.

It will be apparent that on the release of the bolt locking pin from the groove 20, the spring 17 will automatically raise the bolt 14 and permit of movement of the lever 10, or if it is so desired the casing 16 may at this time be removed from the gear case 5. On depressing the bolt 14 when the lever is positioned as in Fig. 1 of the drawings, with the recess 13 below the lower end of the bolt 14, the lower end of the bolt will first pass through the offset portion 19 of the opening 6 thereby locking the casing 16 within the opening 6 and will subsequently be received in the recess 13 locking the lever from movement.

Having thus described my invention, what I claim as new and desire to protect by Letters Patent is:—

1. In combination with a lever casing, a lever movably mounted therein and capable of selective and operative movement in different planes, a locking casing for detachably securing to the lever casing through an opening therein, said locking casing provided with an open ended locking bolt guide, a longitudinally movable foot actuated locking bolt mounted in said guide and of a length to project at its opposite ends beyond the open ends of said guide, the inner portion thereof adapted for engaging with a portion of said lever within said lever casing to lock the lever from operative movement therein, said locking bolt provided in its side wall with a transverse groove, a spring pressed bolt locking pin carried by said locking casing and provided with an elongated tongue for engaging within the transverse groove within said locking bolt to retain the same in locking engagement with said lever, a key controlled locking mechanism cooperating with said pin and capable of operation for withdrawing the same from engagement with said bolt, and a spring for removing said locking bolt

from engagement with said lever and for projecting the outer end thereof beyond the outer end of said locking bolt guide on the release of said locking pin from engagement therewith.

2. In combination with a lever casing, a lever movably mounted therein, said casing provided with an opening adjacent said lever, a mechanism for locking said lever from movement comprising a locking casing for detachably securing within said opening, a member carried thereby for cooperating with the lever to lock the same from operative movement, and a lock controlled device carried by said lock casing for engaging said member to retain the same in locked position relative to the lever, said locking casing being locked from removal from said opening when said member is in locked position relative to said lever.

3. In combination with a lever casing, a lever mounted therein and capable of selective and operative movement in different planes, said casing provided with an opening adjacent said lever, mechanism for locking said lever from movement comprising a lock controlled member carried within a casing for detachably securing to said lever casing through said opening, said lock controlled member adapted for engaging and locking the lever from movement and locking its casing from removal from said lever casing when in said locking position.

4. In combination with a lever casing, a lever mounted therein, said casing provided with an opening adjacent to said lever, mechanism for locking said lever from movement comprising a lock casing for threaded attachment to said lever casing through said opening, a lock controlled lever locking member within said lock casing for engaging said lever to lock the same from movement, said locking member when in locking position intersecting the solid wall portion of said casing and locking said lock and lever casings together.

5. In combination with a lever casing, a lever movably mounted therein, said casing provided with an opening communicating with a portion of the lever within said casing, a lock means for said lever comprising a lock casing for attachment to said lever casing through said opening, a lock controlled locking bolt within said lock casing and capable when in locking position of engagement with the lever to lock the same from movement and of locking said lock and lever casings together, said bolt when in released position being withdrawn from said opening and permitting the detachment of said lock casing from said lever casing.

6. In combination with a lever provided adjacent its lower end with a laterally disposed portion, a fulcrum for supporting said laterally disposed portion and providing a

- fulcrum for the lever, said laterally disposed portion capable of longitudinal movement relative to the fulcrum on the selective movement of the lever, and of axial movement of the fulcrum on the operative movement of the lever, and a lock controlled member for positioning to engage said laterally disposed portion to prevent either selective or operative movement of said lever.
10. 7. In combination with a lever provided with a laterally disposed tubular portion, a member passing through said tubular portion and providing a fulcrum for the lever, said tubular portion capable of movement longitudinally of said member on the selective movement of the lever and of axial movement thereon on the operative movement of the lever, and a locking bolt capable of contact with said laterally disposed portion to prevent either selective or operative movement of the lever.
15. 8. In combination with a lever fulcrumed for operative and selective movement in planes at right angles to each other, said lever provided with an offset portion mounted to provide a fulcrum for said lever, said offset portion adapted to axially rotate in a horizontal plane on the operative movement of the lever and to longitudinally move in a horizontal plane on the selective movement of said lever, and a locking plunger carried by a fixed member and capable of positioning to engage said offset portion to lock said lever in its plane of selective movement.
20. 9. In combination with a lever fulcrumed for operative and selective movement in planes at right angles to each other, said lever provided with an offset portion mounted to provide a fulcrum for said lever, said offset portion adapted to axially rotate in a horizontal plane on the operative movement of the lever and to longitudinally move in a horizontal plane on the selective movement of said lever, and a locking plunger carried by a fixed member and capable of positioning to engage said offset portion to lock said lever from movement.

25. In testimony whereof I have signed my name to this specification in the presence of two subscribing witnesses.

GEORGE C. JENSEN.
